CHARLES L. PAULUS, OF DAYTON, OHIO, AND ROBERT KAUCH, OF CAMP NICHOLS,
PHILIPPINE ISLANDS.

AMMUNITION-FEED MECHANISM FOR MACHINE GUNS.

Application filed August 2, 1926. Serial No. 126,593.

This invention relates to an apparatus for supplying machine guns with ammunition.

One object of this invention is to provide an ammunition feed mechanism for certain 5 types of machine guns such as Browning machine guns which will insure an uninterrupted supply of ammunition and to simplify the placing of the supply of ammunition in a position where it can be fed into the gun 10 in the most efficient manner.

More specifically our invention relates to the mounting of an ammunition feed reel upon a vertical axis directly upon the movable or hinged cover of the machine gun.

15 Due to this arrangement the cover may be easily moved to permit access for purposes of repair or adjustment to the gun. At the same time the ammunition reel is moved out of the way of the operator. The ammunition feed device consists of a moving base 20 with a spiral feed chute and a detachable ammunition spool or reel mounted thereon. Instead of providing a brake for preventing the overrunning of the reel, upon the reel 25 itself, this brake is provided upon the base just mentioned so that the reel may be attached to the brake when it is placed in position on the mounting base.

30 The weight of the cover and of the ammunition and ammunition feed device guide is counterbalanced when the gun cover is raised by means of counterbalancing springs so that the gun cover may be maintained in its open position without any assistance from 35 the operator and the free use of both hands is permitted in making adjustments or repairs to the gun.

The ammunition feed device herein provided 40 may be attached to existing gun covers of the Browning without making any changes in these existing gun covers. For this purpose the ammunition feed base is attached to the feeding pawl holding member of the gun.

45 The reel upon which the ammunition is held is provided with a wooden hub of spiral shape so that a groove is provided within which the first cartridge rests and a smooth unbroken line is provided against which the series of cartridges are placed. The two side 50 discs of the reel are rigidified by ridges formed as radial bulges at their outer portions.

The chute, which leads the ammunition from the reel to the gun is formed as two

separate spaced guide rails, which are held 55 together by spacing strips, the spaces between the two rails for the most part being entirely open so that the cartridges therein are freely accessible to the operator.

With these objects and advantages in view 60 our invention will now be discussed more fully, having reference to the attached specification and drawings, in which

Fig. 1 is a perspective view of the ammunition feed apparatus in position upon a 65 Browning gun.

Fig. 2 is a plan view.

Fig. 3 is a section along the line 3—3 of Fig. 2.

Describing the figures more in detail, 1 represents a machine gun such as a Browning machine gun having a cover plate which is removable for the purpose of viewing the interior mechanism of the gun, the forward end of the cover plate being pivoted on a 75 pin 3.

The apparatus comprising this invention is composed of two main parts, a metallic ammunition spool 4 and a combined spool mount and ammunition chute frame 5, which conveys the ammunition from the spool to the gun. 80

The mounting frame 5 has a base 6 which is provided at one end with a pair of fin like projections 7, the bottom part of which fit 85 down over the cover plate 2. Each of the projections 7 are provided with holes 8 in alignment with each other through which the pin 3 at the front end of the cover plate 2 passes, thereby fastening the frame 4 to 90 the gun. The upper part of the projections 7 are provided with outwardly extending pins 9 each adapted to hold an end of tension springs 10, the other ends of which are fastened to the gun in some convenient manner at 11. The base 6 is also provided with a hole 12 which corresponds with the hole in the cover plate 2, of the Browning gun. Extending through the hole 12 is a key 13 which holds the base firmly in contact with 100 the cover plate. This key is attached to the feed pawl holding member at present in use in the Browning gun so that no changes are necessary in the construction of the gun itself. It will be seen from the foregoing description that the cover plate may be raised with the pin 3 as a pivot without removing 105 the apparatus. The spring 10 is arranged to

hold the cover plate in an open position, thus permitting the operator the free use of both hands in making repairs or adjustments to the gun.

- 5 Near its other end the base 6 is provided with a hollow axle 14 for the ammunition spool to revolve upon at the top and inside of which there is an inwardly projecting flange 15 of a predetermined depth to which the spool may be fastened.

- 10 The spool is made from spring steel and both the top disc end 16 and the bottom disc end 17 are ribbed as at 17' to give added strength to the discs. It is understood that 15 these belts are wound on the spool before placing the same on the axle. For the purpose of securing the spool to the axle the top disc 16 is provided with a flanged handle plate 18, into which is fitted a slide member 20 19 provided at its exposed end with a thumb rest 21 to which is attached a resilient member 22. When the spool is placed in position, this hooked member catches on the inwardly extending flange 15 and prevents the removal of the spool until it is released by pressing the thumb rest 21 inwardly. A strap handle 24 is attached to this handle plate 18.

- 25 When the cartridge belt is placed in position upon the spool the cartridges are prevented from unwinding by the insertion of a pin through the holes 23 provided near the rim of the ends 16, 17 of the spool. The rim of the ends 16, 17 of the spool are flanged outwardly as shown in Fig. 3 to assist the ribs 30 35 17' in maintaining the rigidity of the spool so that it may sustain the heavy weight of the cartridges.

- 30 The rotation of the spool is permitted by a rotating base 25 which is mounted on and 40 revolves upon the fixed axle 14. Within the interior of the base 25 is a spring band 26 which is fixed to base 6 and which prohibits the too free rotation of the base 25 by creating a friction against the flange thereof. 45 There are three conical projections 27 extending upward and spaced apart 120 degrees upon the top surface of the base 25. When the spool is placed in position these projections fit into a series of holes 28 spaced very 50 close to one another in the lower disc 17 of the spool. A large number of holes are provided so that the operator may easily and quickly create the connection without adjusting the spool about its axis of rotation.

- 55 The hub of the spool is further provided with a depression or chamber 29 into which the first cartridge of the belt to be wound upon the spool fits, thus when it is completely wound an even surface results and all of the 60 bullets are in a vertical position. The first cartridge is held by a metal spring clip 24' which is attached to one end of a flexible fabric strap 25', the other end of which is screwed or nailed to the wooden hub of the 65 spool. Thus the last cartridge may be guided

up to the chute and pulled away from its holding clip as the cartridges are fed into the gun.

After the spool has been placed in position the belt is partially unwound and shoved by hand into the spiral guideway or chute 5 which is attached firmly to the base 2. The usual manually rotatable star wheel may be employed to feed the series of cartridges to and along the chute 5, or may be located at the end of the chute adjacent the gun to start the feed of the ammunition to the gun. The guideway conducts the belt of ammunition to the desired point on the gun. Of course it is understood that after the first bullet has been fired, the action of the machine gun effects the further unwinding of the belt and supply of ammunition to the gun. As a result of this method of supply the bullets pass through a more accurate and sure delivery 85 of the bullets to the gun. The guideway consists of two tracks held apart by spacing strips 22' a distance equal to the length of the cartridge. This guideway is not encased but on the contrary is left open to inspection.

The ammunition spool is in a certain position with relation to the spiral guideway or chute. To insure that the spool will always be in its proper position upon replacement and during operation the hook member 23 is of such a length that it fits snugly beneath the flange 15 at all times to maintain the spool in position so that the cartridge chain will be in position to pass along the chute 5. The belt leaves the spool at a tangent when it enters the spiral. When the belt is in position the projectiles are vertical and the spiral chute changes them to a horizontal position in order to be placed in the gun.

We claim:

1. The combination, in an ammunition feed mechanism for a gun having a gun cover of a spiral ammunition guideway and a rotary ammunition holder mounted upon the gun cover.

2. The combination, in an ammunition feed mechanism, of a spiral guideway, a rotary ammunition holder, a base securing the two in juxtaposition, a movable cover plate for a gun and connection means between the cover plate and the base for mounting the feed mechanism on the gun cover.

3. The combination in an ammunition feed mechanism, of a spiral guideway, a rotary ammunition holder, a base securing the two in juxtaposition, a movable cover plate for a gun and connection means between the cover plate and the base whereby the cover plate may be raised without removing the spiral guideway or rotary feed holder.

4. The combination, in an ammunition feed mechanism, of a spiral guideway, a rotary ammunition holder, a base securing the two in juxtaposition, a pivoted movable cover plate for a gun, connecting means between

- the cover plate and the base and means for maintaining the entire combination in an open position.
5. The combination, in an ammunition feed mechanism, of a spiral guideway, a rotary ammunition holder, a base securing the two in juxtaposition, a pivoted movable cover plate for a gun, connecting means between the cover plate and the base and a counter-
10 balance spring member connecting the base to the gun for the purpose of maintaining the entire combination in an open position.
6. The combination, in an ammunition feed mechanism for a gun having a cover plate pivoted on a pin on the gun, of a spiral guideway, a rotary ammunition holder, a base securing the two in juxtaposition, and means to fasten the base to the pin upon which the cover plate is pivoted.
- 20 7. The combination, according to claim 4, and means to fasten the base to the cover plate, comprising in addition to the pivoted pin, a key extending through the base into the cover plate.
- 25 8. An ammunition holder for machine guns comprising a spool adapted to receive a belt of ammunition, the hub of the spool being recessed to receive the first of the series of ammunition.
- 30 9. The combination, in an ammunition feed mechanism for machine guns, of a rotary ammunition holder comprising a spool adapted to receive a belt of ammunition, the hub of which is recessed to receive the first
35 of the series of ammunition and a spiral guideway for conveying the belt of ammunition from the ammunition holder to its source.
- 40 10. The combination in an ammunition feed mechanism for machine guns, an ammunition reel, means for mounting said reel for rotation on the gun, a device for retarding the rotation of the ammunition holder and means for readily detachably connecting said device
45 to said reel.
11. The combination in an ammunition feed mechanism of a spiral guideway, a vertical axle, an interior flange in said axle, a removable spool and means for securing the spool to the axle consisting of a spring hooked member which intercepts the interior flange when the spool is placed in position.
12. The combination in an ammunition feed mechanism of a spiral guideway, a removable rotary ammunition holder, a series of holes in one end thereof, a revoluble base, and means for connecting the ammunition holder to the revolving base, said means comprising a number of upwardly extending projections on the revolving base adapted to conform with the holes in the ammunition holder, said projections being less in number than said holes.
13. In combination in an ammunition feed mechanism for machine guns, a spiral guideway, a removable rotary ammunition spool, a base attached to said guideway, an axle rigid with said base for mounting said spool, a rotatable member on said axle, brake means for said member and means for connecting and disconnecting said spool to said member for simultaneous rotation, said spool and guideway being situated in such relation that the ammunition enters the spiral at a tangent to the hub of the spool.
14. The combination in an ammunition feed mechanism, of a rotary ammunition holder and a spiral ammunition conveying chute, comprising two spaced spiral guideways, said spiral changing the bullets from a vertical position upon their reception to a horizontal one upon delivery from said chute.
15. The combination as set forth in claim 13 said base being horizontally pivoted to the gun.

In testimony whereof we affix our signatures.
